UNITED STATES PATENT OFFICE.

AUGUSTUS CHARLES ARGLES, OF WIMBLEDON, ENGLAND.

EXHIBITING DEVICE.

SPECIFICATION forming part of Letters Patent No. 708,853, dated September 9, 1902.

Application filed March 7, 1902. Serial No. 97,157. (No model.)

To all whom it may concern:

Be it known that I, AUGUSTUS CHARLES ARGLES, a subject of the King of Great Britain, residing at Overdale, Woodside, Wimbleton, Surrey, England, have invented certain new and useful Improvements in Exhibiting Devices, of which the following is a specification.

The object of this invention is improved coin-free apparatus whereby on the insertion of a coin the operator can ascertain the time of trains, tram-cars, omnibuses, or the like to a given destination, station, or stopping-place.

15 My invention will be clearly understood from the following description aided by the accompanying drawings, in which—

Figure 1 is a front elevation of a machine. Fig. 2 is a view of a portion of the side of a machine, showing the sliding collar capable of actuation by the operator previous to exposing the time-table. Fig. 3 is a sectional elevation of a machine. Fig. 4 is a sectional plan of the machine, the guide-plate and buffer-rod having part broken away. Fig. 5 is a front section of an apparatus in which the time-table is lowered for exposure. Fig. 6 is a front sectional elevation of a machine in which the time-table is revolved on a pivot 30 for exposure.

My apparatus in its simplest form consists of a box 2, having within it a number of sheets or holders 1, each containing the times of trains from the particular station to another station on that railway. These sheets 35 are actuated simply by an arm 3 on a collar 8 surrounding a rod 4, which rod is actuated by the operator by the handle 5, situated outside the apparatus, to lift the selected sheet 1 to expose it for view. The side or other part of the apparatus contains the names of all the stations, as at Fig. 2, and by sliding a pointer 6 to the station wanted the lugs 7, which engage the collar 8 of the 40 arm 3, will place the arm under or over the selected sheet 1 to be lifted, so that on the actuation of the handle after the dropping in of a coin the sheet will be lifted, lowered, or revolved and exposed to view. Thus if an 45 apparatus be fixed on Waterloo station and a person desires to know the time of the next train to Aldershot all he has to do is to drop 50

a halfpenny or a penny in the coin-chute. Then he moves the pointer to "Aldershot," this moving the arm and collar along the rod 5 until the arm is situate under or over the Aldershot sheet. Then by actuating the handle the coin 9, which has dropped through the coin-chute 10 into the pocket 11, fitted to the axle 4, will engage with the pin 12, and so lift 60 the spring-controlled locking-lever 13 and allow the arm 3 to lift or lower the Aldershot sheet and expose same for the operator to see the time-table affixed thereon, the coin falling into the money-till, a release of the handle allowing the sheet and the appliance to resume their normal condition. Indications, such as the platform the train starts from, advertisements can be made upon the sheets, and the whole appliance may be used for purposes other than indicating the time of trains, omnibuses, and the like.

According to Figs. 1 to 5 the sheets 1 have legs 14 at one side sliding in grooves of a plate 14^a, the other edges of the plates 1 sliding in grooves of a plate 15 at the other side, so that a proper movement is effected without tilting; but in Fig. 6 the sheet 1 is pivoted on a separate axle 16 and carries a stub 14, which is actuated by the arm 3, the sheet 80 being returned, as in Fig. 5, to its normal position by a spring 17. 18 is a rubber-covered buffer-rod, against which the plates rest when exposed. In Fig. 5 the arm 3 is returned by a spiral spring (not shown) encircling a portion of the rod 4.

Any coin-free mechanism can be employed, the feature of the invention being arranging the times of trains or conveyances from one station to another upon separate 90 sheets and exposing the desired sheets after the insertion of a coin to indicate the times of starting of such conveyances.

What I desire to claim and secure by Letters Patent is—

1. In an exhibiting device, the combination with a casing provided with an exposure-opening, an elongated slot and a plurality of indicating-sheets arranged therein, of a rotatable rod mounted in said casing, a collar adjustable upon said rod, means operating in said slot for adjusting the said collar, an arm integral with said collar, and means engaged and operated by said arm when said rod is

rotated for exposing the said sheets through the said opening.

2. In an exhibiting device, the combination with a casing provided with an exposure-opening, an elongated slot and a plurality of indicating-sheets arranged therein, of a rotatable rod mounted in said casing, a collar adjustable upon said rod, means operating in said slot for adjusting the said collar, an arm integral with said collar, means engaged and operated by said arm when said rod is rotated for exposing the said sheets through the said opening, and a handle connected to said rod.

3. In an exhibiting device, a casing provided with an exposure-opening, a series of

indicating-sheets arranged therein, legs connected to each of said sheets, guides for the said sheets, a slidably-adjustable arm adapted to engage the respective leg of one of the sheets, said arm when operated adapted to move the said sheet for exposure through the said opening of the casing, and means for supporting and operating the said arm.

In testimony whereof I have hereunto set my hand in presence of two subscribing witnesses.

AUGUSTUS CHARLES ARGLES.
